Fig. 1

Fig. 3

FIG. 1 is a perspective view of a crib showing the design of my invention.

FIG. 2 is a side elevation of FIG. 1.

FIG. 3 is a section along line III—III of FIG. 2.

The dominant features of my design reside in those portions shown in full lines on the drawings.

Our design of a crib is characterized by a shaped top and spaced vertical slat members of the configuration disclosed, all as shown.

We claim:

The ornamental design for a crib, substantially as shown and described.
